CLEANING MACHINE

Carl E. Erickson, Kalamazoo, Mich.

Application June 3, 1940, Serial No. 338,541

11 Claims. (Cl. 15—9)

This invention relates to improvements in cleaning machines.

The main objects of this invention are:

First, to provide an improved device for cleaning rugs and the like which is highly efficient and leaves the rug or object cleaned without an undue amount of moisture.

Second, to provide a cleaning device for rugs and the like which may be used successfully by a relatively unskilled operator.

Third, to provide a cleaning device of the type frequently referred to as a shampooing machine which may be readily embodied as an attachment to vacuum sweepers of the brushing type now quite extensively in use.

Fourth, to provide a cleaning apparatus of this type which is simple in its parts and adapted to apply and then remove a layer of sudsy cleaning preparation, to thereby loosen and remove dirt and grime from a rug, carpet or the like.

Further objects relating to details and economies of the invention will definitely appear from the description to follow. The invention is defined in the claims.

A structure embodying the features of the invention is clearly illustrated in the accompanying drawings, in which:

Fig. 1 is a fragmentary side elevation of a vacuum sweeper having my invention embodied therein as an attachment.

Fig. 2 is a fragmentary inverted or bottom view of the structure shown in Fig. 1.

Fig. 3 is an enlarged fragmentary view partially in longitudinal vertical section on line 3—3 of Fig. 2 further illustrating the structural details.

Fig. 4 is a top perspective view of the removable brush casing.

Fig. 5 is an enlarged fragmentary view illustrating details of the air connection and control.

Fig. 6 is a fragmentary view partially in section on line 6—6 of Fig. 3.

Fig. 7 is a fragmentary sectional view generally similar to that of Fig. 6 illustrating the sweeper with the conventional brush for a sweeper of the type illustrated.

I have illustrated the invention as embodied in a vacuum carpet sweeper of the brush type as an attachment or as a structure convertible from the regular type of sweeper to the rug or carpet shampooing or cleaning machine, but it will be understood that my invention may be embodied and is desirable for use in a machine designed solely as a rug, carpet or floor cleaning machine.

In the structure illustrated in the accompany-

ing drawing the reference numeral 1 designates generally a vacuum sweeper of the brush type as exemplified by the machine quite widely used and sold under the trade name "Hoover." Since the structural features and operation of this type of vacuum sweeper are well known I do not describe the same in great detail herein save to state that the machine includes a housing or casing 1 which constitutes a carriage and is provided with a brush chamber 2 in communication with an impeller chamber 3 in which the impeller 4 is mounted and designed to create a vacuum in the brush chamber when operated by an electric motor. This brush chamber in a sweeper of the type illustrated ordinarily carries a brush 5 rotatably mounted therein, this being retained by the plate-like keeper or locking arm 6 fulcrumed on the axle of the supporting wheel 7. These brush supports are retained by the locking lever 8. I refer specifically to these features because they are directly associated with parts that are replaced by parts of my invention when my invention is embodied as an attachment as illustrated. The shaft of the impeller 4 is disposed vertically and has a pulley 9 on the lower end thereof, the belt 10 extending forwardly into the brush chamber for the purpose of driving the brush in a manner to be described, whether the brush is the conventional vacuum sweeper brush 5 of Fig. 7 or a brush such as I embody in my improvements.

When employed as a vacuum sweeper the bottom cover plate 11 illustrated in dotted lines in Fig. 1 is attached to the impeller housing to place the brush chamber in vacuum communication with the impeller chamber. The releasable connection 12 to the impeller housing is provided for this purpose. However, it is to be understood that in use of the machine as a rug scrubbing or shampooing apparatus this cover plate is removed. A bottom cover or retaining plate 13 is likewise removably secured to the bottom of the casing or carriage. These parts in the embodiment illustrated are the parts of the vacuum sweeper.

Referring to Figs. 3, 4 and 6, the reference numeral 14 generally indicates a brush mounting casing and dirt received of integral metal construction adapted to be removably mounted in the brush chamber 2 of the sweeper in place of the usual brush 5. This casing has a brush 15 rotatably journaled in plates 16 secured in the ends of the housing, the latter being slotted at 17 to enable convenient assembly of the brush and brush journaling plates therewith. The cas-

ing 14 is generally arcuate or segmental in outline at the portion thereof rotatably receiving the brush 15, but is provided with a plurality of angularly spaced, inwardly extending, elongated depressions 18 constituting abutments against which the angularly spaced sets of bristles 19 on the brush sweep when the brush is rotated. This rotation of the brush is accomplished by the belt 10 which passes over a center pulley 20 on the brush. The brush casing 14 is braced by ribs 21 in the region of the depressions 18 so as to rigidify the structure.

At the rear side of the segmental brush receiving and mounting portion of the casing 14, the latter extends outwardly to provide a hollow dirt and grime receptacle 22 adapted to receive moist matter swept from the rug in the operation of the apparatus. The forward lower edge of this hollow receptacle is provided with a slight lip 23 which projects radially relative to the brush axis a slight distance inwardly of the extreme peripheral path described by the tufts of brush bristles 19. Hence, the bristles are given a flicking or whip action in passing this lip to flick the moist dirt or grime into the receptacle 22.

The space between the upper forward edge 24 of the receptacle 22 and the adjacent recess 25 in the segmental or brush mounting portion of the casing acts in the same manner as the abutments 18; that is, it extends radially inwardly of the brush axis to a point substantially coincident with the extreme periphery of the bristle travel, so that the bristles wipe against these abutments and tend to flick moist dirt and grime into the successive recesses 25, 26, 27, thereby cleaning the brushes for a subsequent engagement with the rug. A final wiping of the bristles is had by engagement thereof with the lower edge 28 of the recesses 27.

As pointed out above, the closure plate 11 for the vacuum impeller housing is removed when the apparatus is operating as a shampooing machine, there being no vacuum within the casing at such time.

In order to prevent the throwing of moist dirt or grime laterally into the space in which belt 10 is disposed, the receptacle 22 is provided with wall-like splash guards 29 at either side of the space, thereby in effect subdividing the receptacle 22 into two independent receptacles. The outline of a central passage through the receptacle portion 22 of the casing 1 is indicated in dotted lines 30 in Fig. 2. This accommodates the brush driving belt 10.

It will be understood that the casing 14 and brush journaled therein are substituted in their entirety for the conventional vacuum sweeper brush 5, the detent plate 6 of the machine co-acting with the brush journaling member 31 in the same manner as it does when the conventional brush 5 is employed. In this manner the casing 14 and associated parts are operatively held in the housing. The bottom cover plate 13 is applied following mounting of the casing 14 in the vacuum housing to hold the casing therein.

For the purpose of applying a quantity of sudsy cleaning liquid to the rug in advance of the brush 15, I provide a receptacle or tank 32 for the liquid detergent or cleaning agent 33, this tank having a hanger 34 on the rear side thereof engageable in a slot 35 on the front of the brush housing 2 to suspend the tank on the housing. The tank engages the sweeper bumper

36 at its lower rear edge so that a stable support for the reservoir is provided.

The reservoir has a filling opening provided with a closure 37 and has an opening 38 of substantial size at the front thereof defined by the rearwardly and upwardly projecting and overhanging lip 39 over which suds evolved from the cleaning liquid 33 are discharged onto the rug, as illustrated in Fig. 3. For the purpose of generating suds in the tank or reservoir the latter is provided with a vertical air tube 40 communicating with a hollow perforated rod 41 disposed horizontally adjacent the bottom of the tank. Air discharged through the tube 40 and perforations of the hollow rod 41 generates bubbles in the liquid 33 which rise and are discharged over lip 39 onto the rug in the manner illustrated in Fig. 3.

In order to supply air for the generation of bubbles, I connect tube 40 by means of a flexible conduit 42 with a suitable point on the impeller housing, utilizing a fitting 43 extending into the housing for this purpose. It will be evident that the impeller 4 generates a substantial blast of air into the bag of the sweeper, part of which passes through the fitting 43 and tube 42 to the reservoir for the purpose described. An adjustable shut-off valve 44 is interposed in the air line for closing this line when the apparatus is used as a vacuum sweeper and for regulating the amount of air discharged to the reservoir.

From the foregoing it is believed that the operation of my attachment in association with the sweeper will be apparent. When the reservoir 32 is filled with liquid cleaning agent, the cover plate 11 for the impeller housing being removed, and the motor energized to operate the device, a copious quantity of suds is discharged on the rug and immediately thereafter swept up by brush 15 to deposit dirt, grime and the like, loosened and picked up by the suds, in the receptacle 22 or one of the recesses 25, 26, 27, there being no redepositing of the grime on the rug by reason of the cleaning action to which the brush bristles are subjected. I find that the shampooing action is very effective. The parts of the attachment or device making the same possible are simple and relatively inexpensive, and the operation of mounting the attachment on a sweeper to convert the same to a shampooing apparatus consumes but very little time. The ready removability of the brush journaling casting and brush therein enables the same to be easily removed from the sweeper at periodic intervals for flushing out the interior to cleanse the same of dirt, mud, grime, lint and the like which have accumulated therein.

I have illustrated and described my invention in an embodiment which I have found very practical and effective. I have not attempted to illustrate or describe other adaptations which I contemplate as I believe the disclosure made will enable those skilled in the art to embody or adapt the invention as may be desired.

Having thus described my invention what I claim as new and desire to secure by Letters Patent is:

1. In combination with a vacuum sweeper of the brush type, means for readily and quickly converting said sweeper to a rug shampooing device, comprising a combined brush journaling casing and dirt receiver adapted to be mounted in the brush housing of the sweeper in place of the conventional sweeper brush, said casing having an elongated segmental hollow brush jour-

haling portion provided with a plurality of angularly spaced elongated radial projections defining spaced elongated recesses internally of said portion, a rearwardly extending dirt receptacle communicating with said portion at its forward edges, and a rotary brush journaled in said portion having bristles engageable with said projections to flick moist dirt into said recesses, there being a lip adjacent one advance edge of the receptacle engageable by said bristles to cause the same to flick substantial quantities of dirt into said receptacle, and means removably mountable on said sweeper for generating a quantity of sudsy cleaning agent and directing the same downwardly on a rug.

2. In combination with a vacuum sweeper of the brush type, means for readily and quickly converting said sweeper to a rug shampooing device, comprising a combined brush journaling casing and dirt receiver adapted to be mounted in the brush housing of the sweeper in place of the conventional sweeper brush, said casing having an elongated segmental hollow brush journaling portion provided with a plurality of angularly spaced elongated radial projections defining spaced elongated recesses internally of said portion, a rearwardly extending dirt receptacle communicating with said portion at its forward edges, and a rotary brush journaled in said portion having bristles engageable with said projections to flick moist dirt into said recesses, there being a lip adjacent one advance of the receptacle engageable by said bristles to cause the same to flick substantial quantities of dirt into said receptacle.

3. In combination with a vacuum sweeper of the brush type, means for readily and quickly converting said sweeper to a rug shampooing device, comprising a combined brush journaling casing and dirt receiver adapted to be mounted in the brush housing of the sweeper in place of the conventional brush, said casing having an elongated hollow portion and a rearwardly extending dirt receptacle communicating with said portion at its forward edge, a rotary brush journaled in said portion, there being a lip adjacent the lower forward edge of the receptacle engageable by the bristles of said brush to cause the same to flick substantial quantities of dirt into said receptacle, and a pulley on said brush to receive a belt for rotating the brush, said receptacle having partitions therein defining a front to rear space accommodating said belt and preventing lateral splashing of the same by dirt from the brush bristles.

4. A structure of the class described comprising a brush casing having an arcuate brush receiving chamber and a dirt receiving receptacle extending rearwardly of and communicating with said chamber, a brush rotatably journaled in said chamber, means for rotating the brush, said chamber having a longitudinally extending radial projection therein engageable by said brush in its rotation and a recess adjacent said projection to receive dirt flicked from the brush by said engagement, and means operatively connected to said casing for generating a quantity of suds and applying the same to the rug in advance of the brush.

5. A machine of the class described comprising a brush receiving casing, a brush rotatably journaled in said casing, said casing having projections extending radially of the brush axis and engageable by the brush bristles in the rotation thereof and having a plurality of radial recesses

10 adjacent said projections for the reception of dirt flicked from said bristles upon engagement thereof with said projections, and means operatively connected to said casing for generating a quantity of suds and applying the same to a rug in advance of the brush.

6. In combination with a vacuum sweeper of the brush type, means for readily and quickly converting said sweeper to a rug shampooing device, comprising a combined brush journaling casing and dirt receiver adapted to be mounted in the brush housing of the sweeper in place of the conventional sweeper brush, means operatively connected to said sweeper for generating and discharging copious suds on the surface to be cleaned in advance of said casing, said casing having an elongated segmental hollow portion and a rearwardly extending dirt receptacle communicating with said portion at its forward edge, 20 a rotary brush journaled in said portion, said brush having drive means thereon coating with the sweeper brush drive means of, said sweeper, there being a lip adjacent the lower forward edge of the receptacle engageable by the bristles of said brush to cause the same to flick substantial quantities of dirt into said receptacle, and means for removably attaching said casing interiorly of the sweeper brush housing to enable the casing to be readily removed for thorough flushing 25 of the interior thereof.

7. The combination with a carriage, of a longitudinal brush casing having a downwardly facing brush chamber therein, the walls of which are provided with a plurality of internal longitudinal projections alternating with dirt receiving pockets, a driven rotary brush journaled in said chamber on an axis extending longitudinally of the casing, said projections extending parallel to the brush axis and being disposed so that the tips of the brush bristles engage therewith as the brush is rotated to produce a flipping dirt discharge action of the bristles discharging dirt therefrom to said pockets, and means operatively connected to said casing for generating copious suds and discharging the same upon the surface to be cleaned in advance of the brush.

8. In an apparatus of the class described, the combination with a casing having a longitudinal brush chamber and a driven brush rotatably mounted in said chamber on an axis extending longitudinally thereof, said brush chamber having an internal projection extending longitudinally of the brush axis and projecting into the path of the ends of the brush bristles so that on rotation the brush bristles are engaged by the projections to facilitate the discharge of dirt therefrom, of means operatively connected to said casing to generate copious suds and discharge the same on the surface to be cleaned in advance of said brush.

9. In an apparatus of the class described, the combination of a brush chamber having a rearwardly extending dirt receptacle opening thereto, and a driven brush rotatably mounted in said brush chamber, the walls of said brush chamber having internal elongated projections extending longitudinally of the brush axis and projecting into the path of the ends of portions of the brush bristles so that on rotation of the brush the bristles are engaged by the projections to facilitate the discharge of the dirt therefrom, one of said projections being disposed at the forward end of the bottom of said dirt receptacle.

10. In combination with a brush type vacuum sweeper having a sweeper housing, a combined

brush casing and dirt receiver adapted to be removably mounted in the brush housing of the sweeper upon removal of the sweeper brush therefrom, a rotary brush journaled in said casing provided with drive means coaxing with drive means on said sweeper, said casing having an elongated hollow brush journaling portion provided with an internal projection engageable by the brush in the rotation thereof to flick dirt therefrom and with means for receiving dirt flicked from the brush in the rotation of the brush in said casing, and means for removably attaching said casing interiorly of the sweeper brush housing to convert the sweeper to a rug shampooing device, while enabling the casing to be readily removed from said housing for flushing out the interior of the casing to remove dirt and the like therefrom.

11. In combination with a vacuum cleaner having a vacuum housing, a combined brush casing and dirt receiver adapted to be removably mounted in said housing of the cleaner, a rotary brush journaled in said casing provided with drive means coaxing with drive means on said cleaner, said casing having an elongated hollow brush journaling portion receiving dirt picked up by said brush during the rotation of the brush in said casing, and means for removably attaching said casing interiorly of said cleaner housing to convert the cleaner to a rug shampooing device, while enabling the casing to be readily removed from said housing for flushing out the interior of the casing to remove dirt and the like therefrom.

CARL E. ERICKSON.
